MUSICAL INSTRUMENT.

1,195,177.

Specification of Letters Patent. Patented Aug. 22, 1916.

Application filed August 8, 1914. Serial No. 855,868.

To all whom it may concern:

Be it known that we, LAWRENCE G. BERGERON, a citizen of the United States, residing at Lakewood, in the county of Cuyahoga, and State of Ohio, and ROBERT B. BREWER, a subject of the King of Great Britain, and a citizen of the Dominion of Canada, residing at Cleveland, in the county of Cuyahoga and State of Ohio, have invented a certain new and useful Improvement in Musical Instruments, of which the following is a full, clear, and exact description, reference being had to the accompanying drawings.

This invention relates to musical instruments and particularly to those of the percussion type which are played by depressing keys or stops, and the object of the invention is the provision of new and improved means for effecting the percussion whereby a single clear sharp blow may be given to the sounding member and whereby the striking device may be withdrawn immediately after delivering this blow so as not to impede the vibrations.

In the drawings accompanying and forming a part of this application we have illustrated our invention as embodied in a set of chimes, and certain features of the said invention are particularly useful in connection with chimes and will be so claimed, while other features are susceptible of general use and are not so limited.

In these drawings, Figure 1 represents a side elevation of a single chime tube together with a percussion device of our invention, the latter being shown in longitudinal section; and Fig. 2 is a diagrammatic view showing a plurality of chime members with their various keys and connections, the chime members being shown in front elevation.

Describing the parts by reference characters, A represents a base or support of any suitable type and arranged to receive any desired number of chimes, while B—B represent a pair of brackets projecting horizontally therefrom and arranged to support a chime tube C through the medium of a flexible cord D. In Fig. 2 the various chime tubes are shown at C¹, C²—C⁸, indicating a complete octave, all of the members being closed at their upper ends to which these suspending cords D are attached.

Secured to the base or support A in the

rear of each tube is our improved percussion device, consisting of a solenoid 1 held in vertical position by suitable brackets 2 and having projecting in each direction a hollow axial guide tube 3—3 here shown as extending uninterruptedly through the solenoid. Slidably mounted inside of this tube is an armature 4 having at its upper end a fixed pin or peg 5, and loosely received within the tube 3 above the armature is a striking member 6 having at its lower end a socket adapted to receive the peg 5 and at its upper end a striking head 7 preferably cushioned by means of felt, rubber, or other elastic material. The closed end of the tube C is provided with a rigid horizontal arm 8 which extends over and into the path of the striking member 6. The lower end of the tube 3 is provided with a suitable closure 10 receiving a threaded adjusting screw 11 to the upper end of which is attached a spring 12 and buffer 13 arranged to cushion the fall of the armature.

The keys are illustrated at 15¹, 15²,—15⁸ and are arranged to bring movable contact members 16 into engagement with fixed contact members 17 so as to close the circuit through the battery 18 and the respective solenoids. In the present embodiment the movable contacts 16 are connected to the one pole of their respective solenoids by lead wires 20¹, 20²—20⁸ respectively, the opposite poles of the solenoids being connected to a common return wire 21.

The arrangement and adjustment of the screw 11 is such that the upper end of the armature 4 is normally somewhat below the upper end of the solenoid 1, while the length of the striking member 6 and its position relatively to the arm 8 is such that the distance between the head 7 and arm 8 is somewhat greater than the distance between the upper end of the armature and the upper end of the solenoid. Therefore upon the depression of any key 15 so as to close its circuit the armature 4 will be elevated abruptly, but will stop as soon as it reaches the position where it is traversed by the maximum number of lines of force, while the striking member 6, being only loosely supported by this armature, will continue to ascend and will strike the arm 8 a resounding blow, after which it will drop again into contact with the armature 4, thus affording the arm 8 an opportunity to

- vibrate without obstruction. However the arm 8 is preferably connected to a nodal point of the tube C, thus exercising a minimum disturbing action upon the vibrations.
- 5 The blow can be repeated as soon as the armature 4 has been permitted to fall entirely to its normal position in advance of a succeeding impulse. This permits the action to be made as rapid as desired.
- 10 It will be understood that this embodiment is merely illustrative and that we do not confine ourselves to the details of construction and arrangements here disclosed except as the same may be recited in the
- 15 claims hereto annexed or may be rendered necessary by the prior state of the art.
- Having thus described our invention what we claim is:
- 20 A percussion device for the purpose described comprising a solenoid, an armature movably supported therein, and a striking member loosely mounted upon one end of said armature and separable therefrom in the striking operation.
  - 25 2. A percussion device for the purpose described comprising a solenoid, an armature movably supported therein, and a striking member loosely mounted at one end of said armature, said armature being arranged for movement only within narrow limits and said striking member being arranged for movement between wider limits.
  - 30 3. A percussion device for the purpose described comprising a solenoid, an armature movably supported therein, and a striking member loosely mounted upon one end of said armature and separable therefrom in the striking operation, said armature being normally maintained at one end of said
  - 35 40 solenoid and said striking member being arranged at the opposite end of said solenoid from the end at which said armature is normally maintained.
  - 45 4. A percussion device for the purpose described comprising a solenoid, means for supporting said solenoid in upright position, an armature loosely supported within said solenoid and arranged for vertical movement, means normally supporting said
  - 50 armature at a point below the top of said solenoid, and a striking member loosely mounted upon the upper end of said armature and separable therefrom in the striking operation.
  - 55 5. A percussion device for the purpose described comprising a solenoid, means for supporting said solenoid in upright position, a guide member projecting above said solenoid, a striking member movable with respect to said guide member, and an armature within said solenoid and movable along the axis thereof, said striking member being arranged to rest loosely against said armature and separable therefrom in the striking operation.

6. In a percussion device, in combination, a solenoid, a hollow guide member projecting from each end of said solenoid, an armature inside said solenoid and movable along the axis thereof, means carried by 70 one of said guide members and arranged to support said armature normally with its ends displaced axially from the corresponding ends of said solenoid, and a striking member loosely sleeved inside the other guide member and arranged to rest loosely against said armature, whereby it will be expelled upon the energizing of said solenoid.

7. In a musical instrument, in combination, a sounding member of the percussion type, an electromagnetic device, an armature therefor, and a striking member loosely supported upon said armature and arranged upon the energizing of said device to be 80 thrown from said armature and against said sounding member.

8. In a musical instrument, in combination, a sounding member of the percussion type, a percussion member supported for 90 vertical movement and arranged to strike said sounding member upon the conclusion of its upward movement, an electromagnetic device, and an armature loosely supporting said percussion member and co-operating 95 with said electromagnetic device and arranged and adapted upon the energizing of said device to elevate said percussion member, the latter being separable from the armature in the striking operation.

9. In a musical instrument, in combination, a sounding member of the percussion type, a percussion member supported for vertical movement and arranged to strike said sounding member upon the conclusion 105 of its upward movement, an electromagnetic device, and an armature co-operating with said electromagnetic device and arranged and adapted upon the energizing of said device to elevate said percussion member, the range of movement of said percussion member being greater than the range of said armature.

10. In a musical instrument, the combination, with a sounding member of the percussion type and a striking member therefor, of a solenoid supported in upright position beneath said striking member, a vertically movable armature beneath said striking member and normally in loose supporting 115 engagement therewith, the striking member being separable from the armature in the striking operation, and means normally supporting said armature at a point below the position of said solenoid.

11. In a musical instrument, the combination, with a sounding member of the percussion type and a striking member therefor, of a solenoid supported in upright position beneath said striking member, a vertically 120

movable armature beneath said striking member and normally in loose supporting engagement therewith, and means normally supporting said armature at a point below 5 the position of said solenoid, the range of movement of said striking member being greater than that of said armature.

12. In a musical instrument, in combination, a hollow tube suspended from a nodal 10 point, a rigid arm projecting horizontally from said tube, a vertically movable striking member supported below said arm, an armature supported adjacent to said striking member and normally in loose driving engagement therewith, and an electromagnetic 15

device operatively associated with said armature and adapted, when excited, to move same toward said striking member, the distance between the normal position of said striking member and said arm being greater 20 than the free range of movement of said armature.

In testimony whereof, we hereunto affix our signatures in the presence of two witnesses.
